UNITED STATES PATENT OFFICE.

JOHN HAYS HAMMOND, JR., OF GLOUCESTER, MASSACHUSETTS.

PREDIRECTING MEANS FOR TORPEDOES.

Application filed May 13, 1920, Serial No. 381,162. Renewed July 11, 1922. Serial No. 574,285.

To all whom it may concern:

Be it known that I, JOHN HAYS HAMMOND, Jr., a citizen of the United States, and a resident of Gloucester, county of Essex 5 and State of Massachusetts (and whose post-office address is Hammond Radio Research Laboratory, Gloucester, Massachusetts), have invented certain new and useful Improvements in Predirecting Means 10 for Torpedoes, of which the following is a specification.

Some of the objects of the present invention are to provide means for predirecting a torpedo in order that it may follow a pre- 15 determined course when fired; to provide an improved means for setting the angle fire mechanism of a torpedo; to provide means for setting the angle fire mechanism of a torpedo to predirect the torpedo for an angle 20 greater than the angular swing of the deck tube which discharges the torpedo; to provide means for predirecting a torpedo by combining the rotation of the deck tube with the rotation of the angle fire mechanism in 25 the torpedo; and to provide other improvements as will hereinafter appear.

In the accompanying drawings the figure represents a diagrammatic plan of one form 30 of angle fire mechanism for predirecting torpedoes embodying the present invention.

Referring to the drawings a mechanism for predirecting a torpedo by combining the rotation of the deck tube for the torpedo with the rotation of the angle fire mechanism in the torpedo is shown wherein one form of the present invention consists of a deck tube 10 rigidly mounted on a rotatable pedestal 11 of any suitable type having its axis of rotation at 12.

40 For the purpose of limiting the turning movement of the tube 10 to an angle, say of 45°, which is suited to the structure of the vessel upon which the pedestal 11 is mounted, a projection, or lug 13 is rigidly secured to the pedestal 11 and extends radially therefrom to form an abutment to engage one or the other of a pair of stops 14 and 15. In the present instance these stops 14 and 15 are spaced 90° apart and fixedly secured to 45 the deck in the path of movement of the lug 13, each being spaced normally from the said lug 13 by a 45° angle but at opposite sides of the lug 13, whereby an angular movement of the tube 10 in either direction 50 will bring the lug 13 finally into abutting relation with one of the aforesaid stops and

thus prevent further movement of the movable parts. The function of the stops 14 and 15 therefore is to prevent the tube 10 from over-running a specified limit in either 60 direction from a central position.

As a means for turning the tube 10 into any desired position, within the fixed limits an annular member or ring 16 is provided the same being mounted upon suitable bearings to turn about the center 12 as an axis and having its outer periphery formed as a worm gear 17. A worm pinion 18 fast to a shaft 20 is arranged in mesh with the worm gear 17 and the shaft 20 can be turned by 65 means of a hand wheel 21 which is fixed thereon. Suitable bearings 22 for the shaft 20 are provided and may be mounted on the deck or any fixed part. Conveniently located adjacent the hand wheel 21 there is 70 dial 23 which is fixed to the deck and has a pointer 24 which is rigid with the shaft 20 and serves to indicate on the dial 23 the angular position of the ring 16.

For locking the ring 16 to the pedestal 11 80 so that the tube 10 is turned through the given angle by the operation of the hand wheel 21, a pair of lugs 25 are fixed to the ring 16 and spaced to receive between them a plunger 26, which forms the core of a 85 solenoid 27, the connection being a snug fit so that there is substantially no lost motion in either direction. The solenoid 27 is fast to the pedestal 11 and, when de-energized, a spring 30 maintains the plunger 26 out- 90 wardly pressed and interlocking with the lugs 25. Thus any movement of the ring 16 about the axis 12 will be transmitted to the pedestal 11 and tube 10 as long as the solenoid 27 remains in a de-energized condition.

For transmitting the angular movement of the ring 16 to the predirecting mechanism of the torpedo the shaft 20 has a gear 31 fast thereon and in mesh with a second gear 100 32 which is fixed to an armature shaft 33 of a suitable position indicating device 34 which is connected by leads 35 and 36 to a suitable source 37 of alternating current, as for example 60 cycle, 220 volt A. C. The 105 position indicator 34 is constantly in synchronism with the shaft 20 and as here shown the shaft 33 makes one revolution for every five degrees that the ring 16 is moved. The position indicator 34 is electrically connected by leads 40, 41 and 42 to three fixed contacts 43, 44 and 45 respectively, which

are in the path of movement of three movable contactors 46, 47 and 48 carried by a plunger 50, the arrangement being such that when the respective contacts 43, 44 and 45 and contactors 46, 47 and 48 are in contact the position indicator will transmit movement by way of leads 51, 52 and 53 to a position indicator 54 which is arranged to set the torpedo angle fire mechanism by means of a shaft 55.

For maintaining the angle fire position indicator 54 in a zero position, a third position indicator 56 is employed, the same being rigidly clamped in a zero position and connected to the angle fire indicator 54 by leads 57, 58 and 59 through contacts 61, 62 and 63 respectively which are located to be engaged by contactors 46, 47 and 48 which are connected as explained with the position indicator 54. The contactors 46, 47 and 48 are fast to the movable plunger 50.

For the purpose of shifting the plunger 50 it is formed as the common core of two solenoids 71 and 72 which are arranged to be alternately energized by a battery 73 connected at one side by a conductor 74 to both solenoids 71 and 72 and at the other side by a conductor 75, to a contactor 76 fixed to the ring 16 but insulated therefrom. The circuit through the solenoid 71 is completed by way of a ring segment 77 and a conductor 78. The circuit through the solenoid 72 may be completed either through a ring segment 80 and a conductor 81 or through a ring segment 82 and a conductor 83. The three segments 77, 80 and 82 have the same radius and are arranged concentrically with respect to the ring 16 but are insulated one from another by suitable insulation 84.

In order to lock the tube 10 at the end of its swing in either direction, that is against either the stop 14 or stop 15, two solenoids 85 and 86 are fixedly positioned respectively adjacent the said stops 14 and 15, and are included in series in an electric circuit 87, having a battery 88 and two spaced contacts 90 and 91, the latter being arranged to be bridged by a contactor 92 fixed to the plunger 50. The solenoid 85 has a core 93, normally held out of the path of the lug 13 by a coil spring 94 and the solenoid 86 also has a core 95 normally held out of the path of the lug 13 by a like coil spring 96. When the circuit 87 is closed both solenoids 85 and 86 are energized and project the respective cores 93 and 95 into the path of the lug 13, though it will be understood that this action takes place only in a predetermined position of the lug 13 as will be explained.

As a means for energizing the solenoid 27 to release the ring 16 from the pedestal 11 the said ring 16 has a contactor 100 fixed thereto at a point, preferably, diametrically opposite to the contactor 76, and projecting 65 to engage either of two contact strips 101

and 102, according to whether the ring 16 is in one extreme position or the other. Both of the contactors 76 and 100 are electrically separated from the ring 16 by suitable insulation 103. Also in the present instance, the strips 101 and 102 form circular continuations of the ring segments 80 and 82 but are respectively insulated therefrom by insulation 104. The solenoid 27 is a normally open circuit including a battery 105 having a conductor 106 joining the two strips 101 and 102, either of which thereby becomes a terminal, and a conductor 107 connected to the solenoid coil 27. The other end of the solenoid 27 is connected by a conductor 108 with the contactor 100, which forms the other terminal of the circuit, so that whenever the contactor 100 contacts with either of the strips 101 or 102 the circuit is closed, the solenoid is energized and the plunger 26 withdrawn from locking engagement with the lugs 25.

For predirecting the torpedo in the tube 10 any suitable means, not shown, may be provided, such, for example, as a torpedo director of any standard form, which is mounted in any suitable position upon the ship when it will indicate in a well known manner the angle which the course of the torpedo should make with respect to the central position of the tube 10, as shown in the figure. This indicating means may consist of one or more dials mounted in a position so that the desired angle can be read. It is the duty of the operator of the handwheel 21 to keep the pointer 24 on the proper graduation of the dial 23 in accordance with the reading of the dials of the standard director. In carrying out this operation the handwheel 21 is turned, thereby transmitting motion to the worm pinion 18, worm-gear 17, and the ring 16, so that the tube 10 is turned through the number of degrees that are indicated by the dial or dials which are operated from the torpedo director or other predirecting means. As long as the direction which the torpedo should take with respect to the central position remains less than 45°, as in this particular case, the tube 10 is operated in this manner. The angle fire mechanism in the torpedo, during this period is held at a zero position by means of the position indicator 56 which is electrically connected to the position indicator 54 which controls the angle mechanism in the 110 torpedo.

When, however, this angle exceeds 45° the operation is in accordance with the present invention and the following takes place: assuming that the tube 10 is being rotated in a counter-clockwise direction by means of the handwheel 21 and the movement continues until the arm or lug 13 is just about to abut the stop 14, then at that instant the brush or contactor 100 makes con- 125

tact with the strip 101 and thereby closes the circuit through the solenoid 27. This results in the withdrawal of the plunger 26 so that the ring 16 is released from the pedestal or base 11 and can continue its rotation under the action of the handwheel 21, but now moving relative to the pedestal 11. This movement causes the brush or contactor 76 to move off of the segment 77, thus 5 breaking the circuit through the solenoid 71, and as the ring 16 continues to rotate the contactor 76 engages the segment 82 and closes the circuit to energize the solenoid 72. This causes the plunger 50 to be moved to the right, as viewed in the figure, thereby 10 breaking the circuit from the position indicator 56 to the position indicator 54 because the contactors 46, 47 and 48 move out of contact with the contacts 61, 62 and 63, 15 and into contact with the contacts 43, 44 and 45 so that the circuit from the position indicator 34 to the angle fire position indicator 54 is closed. Since the position indicator 34 is arranged to be in a zero position 20 when the ring 16 reaches the 45° angle any additional angular movement of the ring 16 beyond 45° will be transmitted from the position indicator 34 to the position indicator 54 and the latter will turn the shaft 55 25 so that the angle fire mechanism of the torpedo in the tube 10 will be turned through the additional angle above 45° through which the ring 16 has been turned beyond the 45° position. The movement of the plunger 50 to the right also brings the contactor 92 across both the contacts 90 and 91 thus closing the circuit 87 which energizes the two solenoids 85 and 86. The cores 93 and 95 are accordingly moved toward the center of 30 rotation 12 and clamp the arm or lug 13 rigidly against the stop 14 so that the tube 10 is locked in exactly the 45° position.

From the foregoing it will be evident that the ring 16 moves with the base or pedestal so long as the angle is less than 45° during which time the predirecting takes place in the ordinary manner under the influence of the handwheel 21. The ring 16 during this action turns the entire tube 10 until 45 the 45° position is reached. When the angle exceeds 45° the tube 10 is automatically and instantly locked at a 45° angle and further turning of the ring 16 is independent of the tube 10 and the operation is such 50 that the position indicators 34 and 54 turn the angle fire mechanism in the torpedo through the additional number of degrees necessary. When the ring 16 is returned from a position greater than 45° to one less than 45° a reversal of the above described 55 operation takes place and at the moment that the ring 16 passes the 45° point the brush 76 moves out of engagement with the segment 80 and onto the segment 77, there- 60 by deenergizing solenoid 72 and energizing

solenoid 71, thus moving the plunger 50 to the left. This breaks the circuits through the solenoids 85 and 86 thereby releasing the arm 13 and tube 10 and connects the position indicator 54 to position indicator 56 which holds the angle fire mechanism in the torpedo tube at the zero position. At the same time the brush 100 moves out of engagement with the segment 101 thus de-energizing the solenoid 27 which clamps the tube 10 to the ring 16.

Although only one of the many forms in which this invention may be embodied has been here shown, it is to be understood that the invention might be applied in various forms without departing from the spirit of the invention or the scope of the appended claims.

Having thus fully described my invention what I claim is:

1. In an angle fire mechanism, a tube mounted to swing through a predetermined angle, and means for setting a torpedo angle fire mechanism for an angle greater than the limit of swing of said tube.

2. In an angle fire mechanism, a tube mounted to swing through a predetermined angle, and means operative at the end of the swing of said tube for setting a torpedo angle mechanism for an angle greater than the angle of swing of said tube.

3. In an angle fire mechanism, a tube mounted to swing through a predetermined angle, a torpedo angle fire mechanism, means for maintaining said angle fire mechanism in a zero position during the swing of said tube, and means operative at the end of the swing of said tube for setting said angle fire mechanism for a course corresponding to an additional angle beyond said predetermined angle.

4. In an angle fire mechanism, a tube mounted to swing through a predetermined angle as a limit of movement, means for maintaining said angle fire mechanism in a zero position during the swing of said tube, means to lock said tube at the limit of its movement, and means to set said angle fire mechanism to correspond to a course at an angle to the locked position of said tube.

5. In an angle fire mechanism, a tube mounted to swing between certain fixed limits at opposite sides of a central position, a torpedo angle fire mechanism, means for swinging said tube, means operative at the limit of movement of said tube to release said swinging means from said tube, and means controlled by the continued operation of said swinging means to set said angle fire mechanism to correspond to the additional angle of movement of said swinging means.

6. In an angle fire mechanism, a discharge tube for a torpedo, a movable mounting fixed to said tube for turning said tube about a vertical axis, stops for limiting the

- 4
- angular swing of said tube, means for turning said mounting to bring said tube to any angular position between said stops, means for releasing said turning means in a position of said tube abutting either stop, and means for setting said angle fire mechanism for a course greater than the angle determined by said tube at its limit of movement.
- 10 7. In an angle fire mechanism, a discharge tube for a torpedo, a rotatably mounted base fixed to said tube, a ring normally locked to said base, means to turn said ring to adjust said tube for a predetermined angle, means 15 to automatically release said ring from said base at the limit of angular movement of said tube, and means operated by a movement of said ring relative to said tube for setting an angle fire mechanism for an angle corresponding to the turning of said ring relative to said tube.
8. In a mechanism for firing a projectile at an angle to a given axis, a rotatable pedestal, an aiming tube rotatably mounted on the pedestal, means for normally locking the tube to the pedestal so as to rotate therewith, and means automatically operative at a predetermined limit of travel to unlock the same.
- 20 9. In a mechanism for firing a projectile at an angle to a given axis, a rotatable pedestal, an aiming tube rotatably mounted on the pedestal, means for normally locking the tube to the pedestal so as to rotate therewith, and means automatically operative at a predetermined limit of travel to unlock the same.
- 25 10. In a mechanism for firing a projectile at an angle to a given axis, a rotatable pedestal, an aiming tube rotatably mounted on the pedestal, means for normally locking the tube to the pedestal so as to rotate therewith, and means automatically operative at a predetermined limit of travel to unlock the same.
- 30 11. In angle fire mechanism, a rotatable pedestal, a tube positioned thereon and arranged to swing through a predetermined angle with the pedestal, and electrical means for disengaging the tube from the pedestal to permit independent movement thereof when the predetermined angular rotation is exceeded.

Signed at New York, in the county of New York, and State of New York, this 12th day of May, A. D. 1920.

JOHN HAYS HAMMOND, JR.
